Des. 194,535
Patented Feb. 12, 1963

194,535

RIGID AWNING

Bertrand N. Trombley, Bloomfield Hills, Mich., assignor
to Republic Steel Corporation, Cleveland, Ohio, a cor-
poration of New Jersey

Filed Dec. 27, 1961, Ser. No. 68,080

Term of patent 14 years

(Cl. D21—6)

Fig. 1

FIG. 1 is a front perspective view of a rigid awning embodying my new design.

FIG. 2 is a side, sectional view thereof as taken from the indicated line 2—2 in FIG. 3.

FIG. 3 is a rear elevational view thereof.

I claim:

The ornamental design for a rigid awning, as shown.
